UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

BUFFING MECHANISM.

Application filed May 6, 1927. Serial No. 189,202.

This invention relates to buffing mechanisms.

An object of the invention is to provide a buffing mechanism, including a housing containing a main spring means, and preliminary spring means, and a friction system interposed between the main and preliminary spring means together with a buffer head adapted under the influence of relatively light shocks to compress the preliminary springs only, and under the influence of heavier shocks to compress the preliminary springs, actuate the friction system, and compress the main spring means.

Another object of the invention is to provide a shock absorbing mechanism of the character described in which liners are provided which co-operate with the friction shoes of the friction system, and wherein the liners have extensions projecting outwardly beyond one end of the housing to provide substantial guide means for the buffer head of the mechanism, said guide means serving also as stops for limiting the forward movement of the buffer head, which in turn retains the operative parts of the mechanism in assembled condition.

Another object of the invention is to provide a buffing mechanism wherein the liners for the friction system are detachably connected with the housing and maintained in operative position with respect thereto by the wedge and other members of the friction system under the influence of the spring means associated with the mechanism, said liners being so arranged that the forward ends thereof may be spread by the application of pressure to permit the detachable insertion of the buffer head, and inter-engagement of means on the buffer head with stops on the liners, whereby the buffer head is limited in its forward movement and operates to maintain the operative parts of the mechanism in assembled relation with the housing.

Other and further objects of the invention will more clearly and fully appear from the description and claims hereinafter following.

In the drawings forming a part of this specification, Figure 1 is a fragmentary vertical longitudinal sectional view of the end platform of a railway car showing the invention in connection therewith. Figure 2 is a horizontal sectional view taken central-

ly through the buffing mechanism forming the subject matter of the invention. Figure 3 is a front elevational view of said buffing mechanism. Figure 4 is a transverse vertical sectional view of the buffing mechanism, corresponding to the line 4—4 of Figure 2. And Figure 5 is a side elevational detailed view, of one of the liners used in connection with the buffing mechanisms, viewing the liner from the inner side thereof.

As shown in the drawings, 10 represents a portion of the under-framing of a passenger car end platform, 11 denoting the pocket for the reception of a buffing mechanism, indicated broadly by the reference character 12, the buffing mechanism being supported in the pocket by a web 13. The buffing mechanism co-operates with a center stem indicated at 14, the outer end of the stem being engageable by the end platform member 15, which is supported in position by the usual side stems, not shown.

The invention includes broadly a housing A; a main spring means B; liners C; wedge and friction elements D; and a buffing head E.

The housing A is provided with integral top and bottom walls 16—16, side walls 17—17 and an end wall 18, the housing being open at its forward end. Adjacent the forward end of the housing at the inner sides of the side wall 17—17 are provided abutments, in the form of spaced ribs 19 and 20, the inner rib being cut out as indicated at 21. Mounted in the housing is the main spring means B, which comprises a pair of heavy coiled springs arranged side by side and each of the same has associated therewith a smaller coiled spring extending through the center thereof, the rear ends of all of the springs bearing upon the end wall 18 of the housing, while the forward ends of all the springs bear upon the follower 22. The follower 22 is of such a length as to permit the same to be inserted into the housing and removed therefrom, past the abutments 19 and 20, as best shown in Figure 2. The forward face of the follower is provided with a boss 23 adapted to coact with the friction shoes hereinafter referred to to maintain the follower in proper position.

The liners C are two in number, one of the same being associated with each side wall 17—17 of the housing A. Each of the liners comprises the liner portion proper in-

2

dicated at 24, and the extension 25 which provides guide means for the buffer head E as hereinafter described. The liner portion 24 of each liner is provided with an abutment flange 26 extending transversely across the rear end thereof, said flange being adapted to inter-engage with the abutment 20 on the housing A when the parts are in operative position. The inner surface of each liner portion 24 is provided with a friction face 240, for co-operation with the wedge and friction shoes D as herein-after described. At the forward end of each liner portion 24 a rib abutment 27 is provided adapted to bear against the end of each side wall 17. The extension 25 on each liner is integrally formed with the liner portion 24, and consists of a wall of the same width as each side wall 17 of the housing B, the wall being off-set inwardly somewhat with respect to each side wall 17 when the parts are in operative position. The outer surface of the wall providing the extension 25 is provided with a reinforcing rib indicated at 126. The inner surface of the extension 25 of each of the liners is provided with a longitudinally extending centrally disposed groove 28, adapted to provide guide means for the buffer head E as hereinafter described, the groove 28 terminating somewhat inwardly of the extremity of the extension 25 to provide a beveled stop shoulder 29. As above stated, both of the liners C are identically similar except for their opposite disposition, and similar reference characters are employed to indicate like parts of both.

Co-operating with the friction surface 240 of each of the liner portions 24, are the friction shoes D. Each of said friction shoes is provided with a friction face indicated at 30 adapted to co-act with the friction face 240 on the liner portion 24, the opposite side of each shoe being provided with a wedge face 31 adapted for co-action with a similar wedge face on the wedge 32. Each friction shoe is cut out toward the rear end thereof as indicated at 33 and the rear ends of both shoes bear upon the forward face of the follower 22, and are disposed between the shoulders provided by the boss 23 and the rear ends of the liner portions 24. The wedge 32 is provided with a reduced extension 34, providing shoulders 35-35. Bearing upon said shoulders is one end of a coiled spring 36, and a coiled spring 37, the latter extending axially through the spring 36, the outer ends of the springs 36 and 37 bearing upon the buffer head E, and being disposed about a central post 38 formed on the buffer head, the post 38 being adapted to engage the extension 34 on the wedge in certain positions of the parts.

The front face of the buffer head E has inset therein a striking plate 39 adapted to

be engaged by the center stem 14, said buffer head also including a rearwardly extending peripheral flange 40, the side portions of said flange being provided with beveled lugs 41-41 slidably disposed in the guide grooves provided in the liners C, said lugs being adapted to engage the stops 29 on the liners, limiting outward movement of the buffer head E and maintaining all parts of the mechanism in assembled relation, while the side portions of said flange 40 co-operate with the walls of the liner extensions at each side of the grooves 28 and provide substantial guide means for the buffer head.

In operation, assuming a relatively light shock transmitted by the center stem 14 to the buffer head E, said buffer head will move inwardly against the resistance offered by the springs 36 and 37, which bear upon the wedge and friction shoes, which are maintained in their normal positions by the main spring means B, removal of pressure from the buffer head permitting the same to resume its outermost position and held by the stops 29 on the liners C, the buffer head of course being guided during this movement in the grooves 28. A relatively heavy shock transmitted by the stem 14 to the buffer head E will cause inward movement against the preliminary springs 36 and 37 as before described, and additional movement of the buffer head caused by the greater movement of the stem 14 will cause the post 38 to come into contact with the extension 34 on the wedge 32, moving said wedge toward the rear wall 18 of the housing, setting up friction between the friction surfaces 30 and 240 of the friction shoes and the liner portions 24, and causing rearward movement of the friction shoes against the follower 22 which bears upon the main spring resistance B. When the device is fully compressed, the upper and lower edges of the buffer head come into contact with the top and bottom walls of the housing A and hence prevents overloading of the main springs. Upon removal of pressure from the buffer head the various parts will be returned to initial position under the influence of the springs B and 36 and 37.

In assembling the mechanism, the main springs B are first inserted, after which the follower 22 is placed in position. The liners C are then inserted into the housing and the abutments on the liners and housing inter-engaged, and the shoes and wedge are placed in position, as are the springs 36 and 37 and buffer head E. The beveled lugs 41-41 of the buffer head E are positioned to enter the guide grooves 28, after which the buffer head is forced inwardly, temporarily spreading the outer ends of the liners until the lugs 41-41 of the buffer head E move into the guide grooves 28. After the buffer head is in position the liners are held

against spreading by the lateral pressure exerted thereon by the friction shoes and wedge under the influence of the springs 36 and 37, whereby all parts of the mechanism are maintained in assembled relation. When the buffer is placed in the pocket 11 the walls defining said pocket prevent any possibility of the liners accidentally spreading. In practice the side walls of the buffer head E and the extensions of the liners C at opposite sides of the grooves 28 and lugs 41-41 provide large guide and wear surfaces for the buffer head in its movement relative to the liners C, while the guide lugs and grooves in addition to their guiding function maintain the device in assembled relation.

While I have herein shown and described what I consider the preferred manner of carrying out the invention, the same is merely illustrative, and I contemplate all changes and modifications which come within the scope of the claims appended hereto.

I claim:

1. In a shock absorbing mechanism of the character described, the combination with a housing open at one end; of oppositely disposed liners for said housing having abutment means detachably inter-engaged with abutment means on said housing, said liners being provided with extensions projecting beyond the open end of said housing; wedge and friction means adapted to coact with friction surfaces on said liners, and to exert pressure thereon in a lateral direction to maintain said inter-engagement of the abutments on said liners and said housing; a buffer head having lugs inter-engaged with the outer ends of the extensions on said liners; and main yieldable means interposed between fixed portions of said housing and said wedge and friction means, and preliminary yieldable means interposed between the latter and said buffer head.

2. In a shock absorbing mechanism of the character described, the combination with a housing; friction liners for said housing, said liners being provided with extensions projecting beyond one end of said housing to form guide means; a buffer head movably engaging the guide means provided by the liner extensions; and friction means co-operating with said liners to resist movement of said buffer head inwardly of said housing.

3. In a shock absorbing mechanism of the character described, the combination with a housing; liners for said housing provided with friction surfaces, said liners having extensions projecting beyond said housing; a wedge; friction shoes co-operating with said wedge and the friction surfaces on said liners; a main yieldable means interposed between a fixed portion of said housing and

said friction shoes and bearing on the latter; a buffer head operatively engageable with the extensions on said liners; and preliminary springs interposed between said buffer head and said wedge and bearing upon the latter and said buffer head.

4. In a shock absorbing mechanism of the character described, the combination with a housing; liners for said housing provided with friction surfaces, said liners having extensions projecting beyond said housing; a wedge; friction shoes co-operating with said wedge and the friction surfaces on said liners; a main yieldable means interposed between a fixed portion of said housing and said friction shoes and bearing on the latter; a buffer head operatively engageable with the extensions on said liners; and preliminary springs interposed between said buffer head and said wedge and bearing upon the latter and said buffer head, said liners being provided with guide grooves, terminating short of the ends thereof to provide stops, and said buffer head having lugs disposed in said guide grooves.

5. In a shock absorbing mechanism of the character described, the combination with a housing; liners for said housing provided with friction surfaces, said liners having extensions projecting beyond said housing; a wedge; friction shoes co-operating with said wedge and the friction surfaces on said liners; a main yieldable means interposed between a fixed portion of said housing and said friction shoes and bearing on the latter; a buffer head operatively mounted between the extensions on said liners; and preliminary springs interposed between said buffer head and said wedge and bearing upon the latter and said buffer head, said liners having abutments detachably inter-engaging with abutments on said housing, and being maintained in operative relation by lateral pressure exerted by the wedge upon said friction shoes.

6. In a shock absorbing mechanism of the character described, the combination with a housing; liners for said housing provided with friction surfaces, said liners having extensions projecting beyond said housing; a wedge; friction shoes co-operating with said wedge and the friction surfaces on said liners; a main yieldable means interposed between a fixed portion of said housing and said friction shoes and bearing on the latter; a buffer head operatively mounted between the extensions on said liners; and preliminary springs interposed between said buffer head and said wedge and bearing upon the latter and said buffer head, said liners having abutments detachably inter-engaging with abutments on said housing, and being maintained in operative relation by lateral pressure exerted by the wedge upon said friction shoes, the outer ends of said

extensions being separable by the application of pressure thereto to effect operative engagement, and detachment from operative position, of said buffer head with respect to the extensions of said liners.

7. In a shock absorbing mechanism of the character described, the combination with a housing; of liners for said housing having friction surfaces thereon, said liners and said housing being provided with inter-engaging abutments; yieldable means co-acting with said liners and operating to yieldably maintain said abutments in inter-engaging position; extensions rigidly connected to said liners and projecting outwardly of said housing, said extensions being separable by application of power to overcome the yieldable means normally maintaining the liners in position; a buffer head; and means on said buffer head and the extensions of said liners adapted to be inter-engaged to slidably mount the buffer head in said extensions.

8. In a shock absorbing mechanism of the character described, the combination with a housing; of liners for said housing having friction surfaces thereon, said liners and said housing being provided with inter-engaging abutments; yieldable means co-acting with said liners and operating to yieldably maintain said abutments in inter-engaging position; extensions rigidly connected to said liners and projecting outwardly of said housing, said extensions being separable by application of power to overcome the yieldable means normally maintaining the liners in position; a buffer head; means on said buffer head and the extensions of said liners adapted to be inter-engaged to slidably mount the buffer head in said extensions, the yieldable means for maintaining the abutments of said liners and said housing in inter-engaging relation comprising friction elements bearing upon the friction surfaces of said liners; and resilient means bearing upon said friction elements and said buffer head.

9. As an article of manufacture, a friction liner for use in connection with a buffer, comprising a liner portion proper and an extension having means for the reception of a movable member such as a buffer head and providing a combined guide and stop therefor.

55 10. In a shock absorbing mechanism of

the character described, comprising a housing having integral top, bottom, side and end walls, the side walls of said housing being provided with abutments; liners having abutments inter-engaging with the abutments provided by the side walls of said housing, and each of the same having an extension thereon, projecting outwardly beyond the end of said housing, and each extension being provided with a guide groove, and a stop; of a main spring means disposed in said housing and bearing against a fixed portion thereon; a follower for said main spring means; friction shoes co-operating with the friction surfaces of said liners; a wedge; a buffer head having lugs slidably mounted in the grooves in said extensions and adapted to co-operate with the stops thereon to limit outward movement of the buffer head; and preliminary springs interposed between said wedge and said buffer head.

11. In a shock absorbing mechanism of the character described, comprising a housing having integral top, bottom, side and end walls, the side walls of said housing being provided with abutments; liners having abutments inter-engaging with the abutments provided by the side walls of said housing, and each of the same having an extension thereon, projecting outwardly beyond the end of said housing, and each extension being provided with a guide groove, and a stop; of a main spring means disposed in said housing and bearing against a fixed portion thereon; a follower for said main spring means; friction shoes co-operating with the friction surfaces of said liners; a wedge; a buffer head having lugs slidably mounted in the grooves in said extensions and adapted to cooperate with the stops thereon to limit outward movement of the buffer head; and preliminary springs interposed between said wedge and said buffer head, said buffer head and said liners being detachable under pressure and maintained in operative position by the pressure exerted upon the liners by said friction shoes, said wedge and said preliminary springs.

In witness that I claim the foregoing I have hereunto subscribed my name this 3rd day of May, 1927.

STACY B. HASELTINE.
